(57) **CLAIM**

The ornamental design for an electronic lock as shown and described.

DESCRIPTION

FIG. 1 is a front, top, right perspective view of an electronic lock according to the present disclosure.

FIG. 2 is a top view of the electronic lock of FIG. 1.

FIG. 3 is a bottom view of the electronic lock of FIG. 1.

FIG. 4 is a right side view of the electronic lock of FIG. 1.

FIG. 5. is a left side view of the electronic lock of FIG. 1.

FIG. 6 is a front view of the electronic lock of FIG. 1; and,

FIG. 7 is a rear view of the electronic lock of FIG. 1.

The broken lines in the Figures illustrate portions of the article that form no part of the claimed design.

1 Claim, 7 Drawing Sheets
